UNITED STATES PATENT OFFICE

2,634,719

FIREPLACE AND GUARD THEREFOR

Herbert Owen Davies, Coedpoeth, near Wrexham, North Wales, and John Arnold Davies, Oswestry, England

Application December 5, 1951, Serial No. 260,052
In Great Britain December 16, 1950

3 Claims. (Cl. 126—202)

1

This invention relates to fireplaces and aims to combine therewith, as an integral (i. e. normally nondetachable) accessory thereof, a guarding structure which is characterised in that—considered as a whole—it may be readily moved from an out-of-use to an in-use position guarding a fireplace, and so prevent the access of children thereto; and, when not in use, is concealed from view except in respect of plain, or preferably ornamental, terminal members or panels which appear on the sides of the fireplace.

In carrying out our invention, we provide, in the sides or side walls of a fireplace, passages, recesses, or cavities; and permanently, or normally non-detachably, associate therewith portions of displaceable or collapsible guard components of any suitable construction, but such that they may be entered respectively into or through said side passages, recesses or cavities, and will so remain until required for use, when they may be in part withdrawn and moved to guarding position.

The free—i. e. outer—extremities of the respective guard components are associated with terminal panels, or the like, so that, when the guard is not required for use, the panels will abut as stops against the sides of the fireplace and mask the openings of the passages, recesses or cavities, said panels being, preferably, of such shape and colouration as to harmonise with the fireplace.

When it is required to move the guard into position of use, each collapsible or displaceable guard component is withdrawn from concealment by the aid of its terminal panel, or the like, and a foldable part thereof moved across in front of the fire, the two guard components being then connected together in any convenient manner. When the guard is not required, said components are disconnected from one another and readily rehoused, only said stop panels or the like appearing at the front of the fireplace's sides.

To facilitate hand actuation of the guard, said front panels may be fitted with countersunk ring or other handles.

We will further describe our invention with the aid of the accompanying sheets of explanatory drawings, which illustrate, by way of examples only, and not of limitation two modes of embodiment.

In said drawings:

Fig. 1 is a perspective view of a conventional fireplace with a guard consisting of two portions in position of use.

Fig. 2 is a detached view showing the rear of one side of the guard and mode of supporting same.

2

Fig. 3 is a perspective view of the fireplace illustrated in Fig. 1, on the left hand side of which view a guard portion is inwardly displaced and housed behind a side wall surround of the fireplace, and on the right hand side the other guard portion is shown partially collapsed preparatory to being moved inwardly and housed in out-of-use position, or pulled outwardly to position of use, as the case may be.

10 Figs. 4 and 5 are, respectively, part sectional front and side elevations of alternative guide means for the guard components, and Fig. 6 is a rear perspective view of part of Fig. 5 drawn to an enlarged scale.

15 In the several views like characters of reference denote like or equivalent parts wherever they occur.

The guard portions and associated parts of the examples illustrated are of metal, but any other suitable material may be utilised.

20 Referring first to the fireplace and guard illustrated in Figs. 1 to 3, 10 generally represents a fireplace in each side wall 10^a whereof is formed a vertical passage 11 provided at top and bottom with guide components 11^a. Said guides 11^a receive upper and lower horizontal slide bars 12, 12 at the front whereof is secured a vertical panel or escutcheon plate 13 provided with a ring handle 14; at the rear said bars 12 are connected by a stop piece 15. The forward or outward travel of bars 12 is thus controlled by abutment of stop piece 15 against stationary sleeves 11^a whilst their rearward or inward movement terminates on abutment of the associated panel 13 against the side wall 10^a and sleeves 11^a are effectively masked. The rectangular frames formed by rear stop pieces 15, front panels 13 and slide bars 12, 12 are filled in by wire meshwork 16.

25 A rod 17 is secured by its extremities to each pair of slide bars 12 adjacent front panel 13, and pivotally connected at 17^a to rod 17 is a frontal, meshwork-filled, guard portion 18 whereto is hinged (so as to be foldable) as at 19, a co-operating guard portion 18^a.

30 35 Guard members 18, 18^a when folded one upon the other may be pivoted on rods 17, so as to lie in substantially the same plane as bars 12, and so may be pulled or pushed by hand, through the passages 11 of the wall 10^a, to bring the guard into position of use for movement in front of the fire, or to conceal same as may be desired. On extension the foldable members 18, 18^a of each side of the fireplace are secured in guarding position, as shown in Fig. 1, by a bolt 20 (Fig. 2) or in any other convenient manner.

40 45 Referring now to the modification illustrated

in Figs. 4, 5 and 6 of the drawings, through circular apertures 20 with guide sleeves 20^a are formed in the side wall surrounds 10^a of the fire place 10 below and above said passages 11, and slide rods or tubes 21 (being the equivalent of bars 12) carrying the rear pieces 15 and front panels 13, and to which the side guard meshwork 16 is attached, are passed therethrough. In this instance rods 17—whereto are hinged frontal guard portions 18—are mounted on the rear of panels 13 by means of brackets 13^a; and panels 13 are secured to slide rods 21 by internally screw-threaded shanks 21^a of slide rods 21 and screws 22.

In application of our invention to a metal fireplace, such as a kitchen grate, said guides 11^a or sleeves 20^a may be cast on the side walls of the surround during manufacture.

If desired, a provided foldable or other protector top may be fitable to a guard, as heretofore described, so that the fireplace may be completely enclosed.

The distance of the guard, when in use, from a fire is, of course, such that its front will not become unduly heated, and when not required for the protection of children, the guard may be utilised to dry or air clothing and like articles.

If desired, provision may be made for the folding and retirement of a guard's components to their concealed positions to be facilitated by spring assistance.

What we claim as our invention and desire to secure by Letters Patent is:

1. In combination, a fireplace having side walls provided with vertically extending passages, upper and lower horizontal guides provided in said wall passages, bars each slidably mounted in one of said guides, a panel plate secured at the front of said slide bars, a stop member connecting the rear ends of said slide bars, guard meshwork filling the rectangular frame created by said slide bars, said front panel, and said rear stop member, and which constitutes when in use a guard component located at a side of said fireplace, a vertical rod secured adjacent said front panel, a pair of foldable meshwork-filled guard

frames pivotally supported on said vertical rod and constituting when in use guard components located at the front of said fireplace, and means for detachably associating the meeting ends of both pairs of said foldable front guards within position of use, the arrangement being such that each side guard component and pair of associated front guard components may pass into and through a wall passage when not required for use and are concealed from view by said panel plate.

2. In combination, a fireplace and guard components as claimed in claim 1, in which guides are secured within said wall passages for the reception of said slide bars, and said vertical rod whereto is pivoted said pair of foldable front guard components is connected by its ends to said upper and lower slide bars.

3. In combination, a fireplace and guard components as claimed in claim 1, in which said side guides of the fireplace wall are in the form of sleeves and said slidable bars are of circular section, and the vertical rods whereto said front guard components are pivotally joined are connected with said front panels at points respectively below and above said side guard carrying bars.

HERBERT OWEN DAVIES.
